TORPEDO NET

Filed March 6, 1945

INVENTOR:
GORDON H. BANNERMAN,

by: John E. Jackson
Attorney.

UNITED STATES PATENT OFFICE

2,404,612

TORPEDO NET

Gordon H. Bannerman, Hamden, Conn., assignor
to The American Steel and Wire Company of
New Jersey, a corporation of New Jersey

Application March 6, 1945, Serial No. 581,312

4 Claims. (Cl. 114—241)

1

This invention relates to a torpedo net having a mesh structure. There are two types of torpedo nets in general use: one type being used to protect moving vessels, and the other type being used to protect stationary objects. The nets may also be divided into two classes in regard to the manner in which the torpedo is caught: one type catches the torpedo by the propeller, and the other type catches the torpedo by its nose. In the nose catching type, the mesh is generally of an interwoven grommet design except a new type which is secured at each intersection by a fixed clip and is disclosed in the co-pending application of Alan E. Brickman, entitled "Torpedo net and method of making the same," Serial No. 581,310, filed March 6, 1945. In the propeller catching type, the mesh is connected so as to slip at the intersections. Regardless of the type of net, however, it may break due to the shock of the torpedo hitting it and therefore I propose to use a shock absorbing connection in the net to protect it against breakage.

It is, therefore, an object of my invention to provide a torpedo net structure having a shock absorbing seam incorporated therein.

This and other objects will be more apparent after referring to the following specification and attached drawing, in which:

The single figure shows the shock absorbing seam of my invention.

Referring more particularly to the drawing, the reference numerals 2 and 4 indicate two sections of mesh structure which are to be connected by the shock absorbing connection of my invention. Between the two sections are located two substantially parallel wire structures 6 and 8 which are fastened together by fixed connectors 10. Connecting the wire structure 8 and section 2 is a pair of wire structures 12 and 14 which are arranged in a zigzag weave and fastened together by means of slip connections 16. These connections are preferably of the type disclosed in the co-pending application of Alan E. Brickman, Serial No. 581,311, filed March 6, 1945, but other types of slip connections may be used. The wire structure 12 is fastened to the wire structure 8 by means of fixed connections 18 which are located between connectors 10. The wire structure 14 is connected to section 2 by means of connectors 20, fastened to the apices of the mesh structure. Section 4 and wire structure 6 are connected in like manner by means of a slip joint made of wire structures 22 and 24 arranged in a zigzag weave and fastened together by means of slip connections 26, the wire 22 being fas-

2

tened to wire 6 by means of a fixed connection 28, and the wire 24 being fastened to section 4 by connectors 30. When a torpedo hits the net, the wires 6 and 8 will separate as shown in dotted lines to take up the initial shock, and then the wires 12 and 22 will slip with respect to wires 14 and 24, respectively, to absorb more of the shock. If used in a propeller catching net, the clips fastening the mesh together will be slip clips, preferably of the construction described in the above mentioned patent application. However, the slip clips 16 and 26 are designed to slip at a lower pressure than the clips connecting the mesh so that when a torpedo hits the net, the shock is first taken up in the manner described above, and finally the slip connections of the mesh will slip, thus preventing breaking of the net.

In case of a nose catching type of net, the clips fastening the net together are of the non-slipping type preferably of the construction described in the pending application of Alan E. Brickman, Serial No. 563,286, filed November 13, 1944. The shock absorbing seam may be arranged horizontally, vertically, or at an angle therebetween. In some instances, only one slip seam need be used. When the shock absorbing seam is a horizontal seam, the wire 8 may be fastened directly to the head rope in the same manner as it is fastened to the wire 6.

30 While one embodiment of my invention has been shown and described, it will be apparent that other modifications and adaptations may be made without departing from the scope of the following claims.

35 I claim:

1. A torpedo net structure or the like comprising at least two sections, a pair of stranded wire structures, slip connections fastening the two wire structures together, means for connecting one of said wire structures to one section, a stranded wire structure adjacent the other section, a plurality of connections between the last named wire structure and the second section, and means intermediate the last named connections for connecting the last named wire structure to the second of said pair of wire structures.

2. A torpedo net structure or the like comprising at least two sections, a pair of substantially parallel stranded wire structures between said sections, means for connecting said wire structures at spaced intervals, a slip seam between each wire structure and the adjacent section, each of said slip seams comprising two stranded wire structures arranged in a zigzag weave, slip connections fastening the two wire structures of

each slip seam together, means for connecting one of said wire structures of each slip seam to the adjacent section, and means intermediate the first connecting means for connecting the other of said wire structures to the adjacent one of the pair of wire structures.

3. A torpedo net structure or the like comprising a pair of mesh sections having slip connections, a pair of stranded wire structures, slip connections fastening the two wire structures together, the second named slip connections slipping in advance of the first said slip connections, means for connecting one of said wire structures to one section, a stranded wire structure adjacent the other section, a plurality of connections between the last named wire structure and the second section, and means intermediate the last named connections for connecting the last named wire structure to the second of said pair of wire structures.

4. A torpedo net structure or the like comprising a pair of mesh sections having slip connections, a pair of substantially parallel stranded wire structures between said sections, means for connecting said wire structures at spaced intervals, a slip seam between each wire structure and the adjacent section, each of said slip seams comprising two stranded wire structures arranged in a zigzag weave, slip connections fastening the two wire structures of each slip seam together, the second named slip connection slipping in advance of the first named slip connections, means for connecting one of said wire structures to the adjacent section, and means intermediate the second named connecting means for connecting the other of said wire structures to the adjacent one of the pair of wire structures.

GORDON H. BANNERMAN.
